CLAIM

The ornamental design for a barbecue fork, as shown and described.

DESCRIPTION

A utensil for cooking and/or serving food.

FIG. 1 is a front plan view of a barbecue fork according to my design;

FIG. 2 is a left side thereof;

FIG. 3 is a front left perspective of the fork prongs;

FIG. 4 is a bottom left perspective view of the barbecue fork showing detachable thermometer;

FIG. 5 is a bottom perspective view showing the thermometer partially inserted; and,

FIG. 6 is bottom left perspective view of the barbecue fork including a compartment having a corkscrew apparatus stowed therein.
